ABSTRACT

A buckstay system for supporting and reinforcing the tubular walls of a vapor generator including a grid adjacent to the walls and means permitting vertical and horizontal movement between the grid and the adjacent wall along the plane thereof.

SUPPORT OF TUBE WALLS

BACKGROUND OF THE INVENTION

This invention relates to support arrangements for vapor generators and more particularly to an arrangement permitting horizontal and vertical thermal expansion of a top-supported vapor generator.

The support arrangement associated with a top-supported vapor generator comprises ground-supported upright structural steelwork and cross beams associated with the upper portion thereof and including hangers depending from the cross beams to provide support for the vapor generator and associated components. As the vapor generator is brought up to operating temperature, the tubes associated therewith undergo horizontal and vertical thermal expansion, the latter being from a fixed reference point at the top of the vapor generator and being cumulative so as to result in as much as 25 inch movement at the bottom of a very tall utility type vapor generator.

The walls associated with the vapor generator are formed by upwardly extending parallel tubes having their intertube spacing closed throughout substantially all of their length by metallic webs welded to adjacent tubes to provide a gas-tight construction, this type of construction is commonly known as a membrane wall. The strength of a membrane wall is limited and is generally not capable of withstanding the weight of the support arrangement required to maintain its integrity. The membrane wall support arrangement comprises a framework disposed in surrounding relationship to the vapor generator and includes a plurality of horizontal buckstays linked to vertical support beams with the latter being suspended from the structural steel cross beams through appropriate hangers. A plurality of connecting members are employed in linking the membrane walls to the vertical support beams and associated buckstays. The ends of each of the connecting members is formed with a clevis which is in turn linked to the adjoining structure, be it a tie-bar associated with the membrane wall or one of the vertical support beams or the buckstay associated therewith.

Heretofore the arrangement of clevis type connecting members has required the use of bolts having an axial length greater than the maximum vertical thermal expansion of the vapor generator and of a diameter structurally compatible with this length, i.e. 29 inch length and 2 1/4 inch diameter. It is the object of this invention to provide an arrangement which would replace the aforementioned bolt with one having approximate dimensions of 3 1/8 inch length and 1 inch diameter.

SUMMARY OF THE INVENTION

In accordance with the present invention an improvement is made on clevis type connecting members associated with a top-supported vapor generator eliminating the requirement that bolts associated therewith have an axial length exceeding the maximum length of vertical thermal expansion of the vapor generator associated therewith and corresponding to the level at which the connecting member is applied.

The improvement comprises a retaining member having a C-shaped cross-section which is welded either to one of the vertical support beams or one of the membrane wall tie-bars. The retaining member is thus formed with a T-slot extending along the longitudinal

length thereof and arranged to receive the base portion of the clevis-end of a corresponding connecting member. The longitudinal extent of the T-slot is parallel to the axis of the clevis bolt and the retaining member is disposed so as to rigidly restrain the clevis associated therewith in all directions perpendicular to the axis of the bolt thereby allowing the connecting members to be loaded in tension or compression.

The retaining member may be manufactured by weldably joining appropriately sized elongated flat plate strips to form a C-shaped cross-section configuration which engages the base portion of one of the clevises associated with a connecting member in such fashion as to allow vertical movement within the retaining member. The clevis associated with the other end of the aforementioned connecting member is weldably attached to an adjacent tie-bar which is in turn rigidly connected to the membrane wall. The tie-bar is disposed contiguous to the wall and is rigidly held thereon by clamps each of which comprises a pair of scalloped bars welded to the membrane wall and accommodating a restraining pin extending therethrough and over the tie-bar. In this manner, tensile and compressive stresses are distributed over a wider area of the membrane wall while at the same time avoiding additional stresses which may be generated by a differential in thermal expansion between the wall and the associated tie-bar. Furthermore, the weight of the support arrangement is transmitted to the ground-supported structural steelwork and not to the membrane wall.

At some locations of the vapor generator, i.e. the ends of the horizontal buckstays associated with the surrounding wall support framework, the arrangement is such that the buckstay is rigidly attached to the clevis end of a corresponding connecting member while the opposite clevis end is slidably engaged with the retaining member of a vertical support beam in accordance with the invention, the vertical beam being in turn weldably attached to a gusset plate and the latter being weldably attached to a corresponding tie-bar.

The present invention results in considerable simplification of manufacture in that all the support elements are of substantially the same construction and have substantially the same dimensions whether rigidly connected at the membrane wall or at the buckstay.

BRIEF DESCRIPTION OF THE DRAWINGS

FIG. 1 is a schematic sectional elevation showing the furnace chamber and associated support arrangement suspended from the top of ground-supported structural steelwork.

FIG. 2 is a detail partial view taken along line A—A of FIG. 1.

FIG. 3 is a detail partial view of the area designated as B on FIG. 1.

FIG. 4 is a detail plan view taken along line C—C of FIG. 3.

FIG. 5 is a detail side elevation taken along line D—D of FIG. 2.

DESCRIPTION OF THE PREFERRED EMBODIMENTS

FIG. 1 illustrates a top-supported upright furnace chamber 1 comprising fluid heating tubes arranged to form a gas-tight boundary. The furnace chamber 1 is of substantially rectangular cross-section and is defined by two pairs of opposed membrane walls 2 wherein the

lower end of one of the pairs slopes inwardly to form a furnace hopper, and the upper portion of one of the walls formed with an opening discharging into a gas passage (not shown). The membrane walls 2 are provided with tie-bars 3 rigidly attached to the outside of the walls. The vapor generator and furnace chamber associated therewith are suspended from ground-supported structural steelwork including upright columns 20 and cross beams 5. The tie-bars 3 are rigidly connected to the cross beams 5 so as to supportedly connect the membrane walls to the structural steelwork while permitting downward vertical movement resulting from thermal expansion. A furnace hopper support system 4 is attached to the tie-bars 3 and moves with it in response to thermal expansion.

The wall support arrangement associated with the furnace chamber includes a plurality of vertically spaced horizontal buckstays 6 disposed around the chamber 1 and laterally spaced from the walls 2. The buckstays 6 have the primary function of providing lateral support for the membrane walls, however they may also serve as walkways around the furnace chamber 1. The buckstays 6 are connected to a plurality of vertical support beams 7 which are preferably I-beams. The support beams 7 are uniformly spaced about the outer periphery of the furnace and are supportedly connected to the structural steelwork by hanger rods 8 depending from the cross beams 5.

During the operation of the vapor generator, the membrane walls 2 attain an elevated temperature and in turn heat up the tie-bars 3. This rise in temperature causes a downward thermal expansion in the direction of arrow E relative to the vertical support beams 7 which remain generally at ambient temperature. This downward thermal expansion is cumulative and will, in the case of a very tall vapor generator, result in a bottom movement of approximately 25 inches. The connecting members 21 linking the tie-bars 3 to the vertical support beams 7 must be capable of transmitting horizontal tensile and compressive forces of up to 2½ tons per member from the membrane wall 2 to the support beams 7 while at the same time permitting the walls to thermally expand in the direction of arrow E.

As shown in FIGS. 3 and 4, each connecting member 21 consists of a double flange central portion 9 being formed with a clevis portion 10 at one end thereof and a clevis portion 11 at the other end thereof and including a bolt 12 associated with each of the clevises. The longitudinal axes of the bolts 12 of a respective connecting member 21 are disposed parallel to one another. In accordance with the invention the clevis 10 is rigidly connected to the tie-bar 3, preferably by welding, while the tie-bar itself is rigidly held onto the membrane wall 2 by a clamping arrangement consisting of a pair of scalloped plates 13 straddling the tie-bar and a pair of retaining rods 14 extending through the plates 13 and over the tie-bar 3; the plates 13 being weldably attached to the membrane wall 2. The clevis 11 is attached to a corresponding vertical support beam 7 in such manner as to prevent its movement in any horizontal direction while permitting it to slide in a vertical direction. This is accomplished by providing the clevis 11 with a base portion 15 which fits into a C-shaped slot 16 formed by a retaining member 17, the latter being weldably attached to the support beam 7.

An alternate arrangement is shown in FIGS. 2 and 5 wherein the buckstays 6 have their respective ends anchored through the use of connecting members 21' having central portions 9' and including clevises 10' and 11' and bolts 12' associated therewith. The base portion 15' of each of the clevis brackets 11' is inserted into the vertical groove or slot 16' fitted on the support beam 7' so that the clevis 11' is free to slide in a vertical direction. The vertical support beams 7' are weldably attached through respective gusset plates 18 to the tie-bars 3 thereby providing a rigid connection to the corresponding membrane wall 2. This alternate arrangement of connecting members 21' is used to anchor the buckstays 6 and allows the forces shown as arrow F to be transmitted to the membrane wall 2 along a wide area and through the support lugs 19 to be thereby divided into smaller anchor forces as shown by arrow G.

It should be noted that the bolt and clevis arrangement associated with the connecting members 21 permits unrestrained horizontal thermal expansion in a direction parallel to the planar surface of the membrane wall while providing the means for transferring from the wall to the buckstays those forces which are due to tension and compression and which act in a direction normal to the planar surface of the membrane wall. The vertical thermal expansion is compensated for through the sliding arrangement between the selected clevis base portion 15 and the retaining member 17 associated therewith. During start-up of the vapor generator all connecting members 21 move in a downward direction as shown by arrow E in FIG. 3 along with the membrane wall to which they are rigidly attached. As the membrane wall 2 expands downward, the base portion 15 of clevis 11 moves in the direction of arrow E with its edges sliding within the slot 16 while also transferring the horizontal tensile and compressive forces from the wall through the vertical support beams 7 to the horizontal buckstays 6.

The ends of the buckstays 6 are provided with stress-free compensation with respect to the differential in thermal expansion at the anchoring points by virtue of the sliding provision between the connecting members 21' and corresponding support beams 7' in the direction of arrow E as shown in FIG. 5. Each of the clevises 10' is rigidly attached to a corresponding buckstay 6 while each of the clevises 11' is slidably engaged with a corresponding member 7' through the clevis base portion 15' and the retaining member slot 16'.

During the cooling of the boiler a stress-free contraction takes place in a direction opposite to that of arrow E. During steady state conditions whether cold or hot, the differences in thermal expansion are fully compensated.

While in accordance with the provisions of the statutes there is illustrated and described herein a specific embodiment of the invention, those skilled in the art will understand that changes may be made in the form of the invention covered by the claims, and that certain features of the invention may sometimes be used to advantage without a corresponding use of the other features.

The embodiments of the invention in which an exclusive property or privilege is claimed are defined as follows:

1. A fluid heating unit comprising a pair of spaced upright walls defining therebetween a chamber for the

flow of heating gases, a buckstay system disposed outside of the chamber and means connecting the buckstay system to said walls for lateral support and reinforcement thereof, a rigid support structure extending above said chamber, support members separately connecting the walls and the buckstay system for pendent support therefrom, the buckstay system and the walls being subject to different rates of linear thermal expansion, said buckstay system including a grid adjacent each of said walls, each of the grids including at least one horizontal structural member and at least one vertical structural member, said vertical member being disposed between the horizontal member and the adjacent wall, and said connecting means including a plurality of elongated members at least one of which has one end rigidly connected to the adjacent wall and the other end slidably engaged with the vertical member to

permit relative vertical movement between the grid and the adjacent wall along the plane thereof.

2. A fluid heating unit according to claim 1 wherein the remaining of said elongated members have one end rigidly connected to the horizontal member and the other end slidably engaged with the vertical member.

3. A fluid heating unit according to claim 1 wherein each of the ends of each of the elongated members includes a pin and clevis arrangement to permit relative horizontal movement between the grid and the adjacent wall along the plane thereof.

4. A fluid heating unit according to claim 3 wherein the clevis includes a base portion and the vertical member is provided with a retaining clip for engaging said base portion.
